S. G. WEBSTER.
PICKER CHECK.
APPLICATION FILED JULY 3, 1918.

1,325,065.

Patented Dec. 16, 1919.

UNITED STATES PATENT OFFICE.

SHIRLEY G. WEBSTER, OF GLEN RAVEN, NORTH CAROLINA.

PICKER-CHECK.

1,325,065.

Specification of Letters Patent. Patented Dec. 16, 1919.

Application filed July 3, 1918. Serial No. 243,168.

To all whom it may concern:

Be it known that I, SHIRLEY G. WEBSTER, a citizen of the United States, residing at Glen Raven, in the county of Alamance and State of North Carolina, have invented a new and useful Picker-Check, of which the following is a specification.

The subject of this invention is a picker check intended for use on looms for checking the picker stick.

Another object of the invention is the provision of means contacting the toe of the shoe for checking the picker stick.

Another object of the invention is the provision of adjustable picker checking means.

Another object of the invention is the provision of a picker check which may be used on either side of the loom.

The invention also contemplates generally improving the construction and enhancing the utility of picker checks.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawing, wherein:

Figure 1 is a view in side elevation of a check constructed in accordance with the invention, a portion broken away, and the device shown applied;

Fig. 2 is a view taken on the line 2—2 of Fig. 1;

Fig. 3 is a detail view taken on the line 3—3 of Fig. 1, parts being removed.

Referring to the drawing by numerals of reference:

The usual end casting is indicated by the numeral 1 and is adapted for attachment to the ends of the rock shaft of the loom by means of the set screws 2. The casting is formed with the usual upstanding lug 3 which projects through a slot (not shown) which is formed in the shoe 4.

The shoe 4 is mounted to rock on the casting 1, and is apertured to receive a bolt 4'

which serves to clamp the picker stick 5 and the heel strap 6 in place.

The heel strap 6 is apertured in its lower end to receive the hooked end 7 of a coiled spring 8, which end projects through an aperture formed in the circumference of the coil box 9. The spring 8 and the coil box 9 are supported by a bracket arm 10 which depends from one side of the casting 1, and they are joined thereto by means of a bolt 11. The coil spring 8, through the heel strap 6, serves to return the picker stick to normal position, as will be readily understood by those skilled in the art.

The device forming the subject of this invention consists of a bracket arm 12 which is adapted to be secured to the casting 1, and is herein shown as apertured in its lower end to receive the end of the bolt 11 by which the bracket is secured to the bracket arm 10. The bracket 12 rises above the casting 1 and merges, at its upper end, into an angularly disposed portion 13 which is spaced from and overlies the shoe 4.

The angled portion 13 of the bracket 12 is apertured to receive a bolt 14 or the like which serves to clamp one end of the curved leaf spring 15 to the portion 13. The curved spring 15 is of substantially U shape and depends from the angled portion of the bracket 12, terminating above the shoe 4 with its free end practically parallel with the upper surface of the toe of the shoe.

The free end of the spring 15 is provided with a longitudinal slot 16 through which extends a screw bolt 17 which clamps a block 18 in place upon the spring. The block 18 may be formed of any suitable material, but is preferably made of wood, and this block normally rests upon the toe of the shoe 4.

It will be noted that the rear end of the block is herein shown as undercut to avoid the lug 3 so that the block may rest properly upon the toe of the shoe.

It is also to be understood that, though the resilient element is herein described as a curved leaf spring, the applicant does not intend thereby to limit himself to such construction, as any form of shock absorbing element may be used without departing from the idea and intent of this invention.

In practice the device is operated in the following manner:

The attachment is secured to the casting 1

as heretofore described, and the block 18 is adjusted to properly contact the toe of the shoe 4. When the loom is in operation, the picker stick 5 and the shoe 4 rock in unison and, on the forward motion of the stick and shoe, the toe of the shoe parts slightly from the block 18, but, on the return motion, the toe of the shoe contacts the block 18 so that the yielding, shock absorbing element 15 is brought into play to check the motion of the stick, thus saving the shuttle from the usual violent jar and consequent injury.

As the wear member 19 in shoe 4 and the adjacent parts become worn, the shoe moves forward, and the block 18 may be adjusted to proper position by loosening the screw bolt 17 to permit the bolt to slide in the slot 16 until the block is brought to proper position, when the bolt may be tightened to clamp the block in place.

It will be noted that, by reversing the element 15, through loosening the bolt 14, the device is in position to be used on the casting at the opposite end of the loom.

Having thus described the invention, what

is claimed as new and sought by Letters Patent, is:—

1. A picker check, including a picker stick, an attached shoe, a support upon which the shoe rocks, a bracket arm attached to the support and overlying the shoe, a yielding element depending from the bracket, and a block secured to the yielding element and resting upon the toe of the shoe. 30 35

2. A picker check, including a picker stick, a shoe attached thereto, a support upon which the shoe rocks, a bracket arm attached to the support and having an angled end overlying the shoe, a yielding element attached to and depending from the angled end, a block secured for adjustment to the yielding element, and means for holding the block in adjusted position. 40

In testimony that I claim the foregoing 45 as my own, I have hereto affixed my signature in the presence of two witnesses.

SHIRLEY G. WEBSTER.
